UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

RADIATOR CAP.

Application filed December 1, 1921. Serial No. 519,038.

The present invention relates to closure-fastening means, and has for its primary object the provision of improved means embodied in an automobile radiator cap for securing the cap and any instruments or ornaments associated therewith against removal while permitting of a limited displacement of the cap sufficient to give unobstructed access to the interior of the radiator through the nipple thereof which is normally closed by the cap.

While the foregoing statement is indicative of the general nature and purpose of the invention, other objects and advantages which are not specifically set forth will be obvious upon a full understanding of the present device, the invention consisting substantially in the novel construction, combination and arrangement of parts herein-after fully described, illustrated in the accompanying sheet of drawings, and finally pointed out in the appended claims.

Although this disclosure is confined to one particular structural embodiment, it is to be understood that the same is presented here entirely for the purpose of exemplification, and is not intended to be construed as limiting the invention short of its true and most comprehensive scope in the art.

In the drawings—

Fig. 1 is a side view of a radiator cap assembly embodying the features of this invention, portions of the construction being shown in vertical section;

Fig. 2 is a similar view of the assembly taken substantially at right angles to Fig. 1 and showing the cap in its open position;

Fig. 3 is a top plan view of the sleeve associated with the radiator nipple;

Fig. 4 is a side view of the anchor for the cap;

Fig. 5 is a vertical section of the meter-retaining nut;

Fig. 6 is a bottom plan view thereof; and

Fig. 7 is a side view of the set screw used with the retaining nut.

Referring now with more particularity to these views, it will be noted that the radiator nipple 10 has mounted thereon a cap 11 of the commonly designated "bar" type which in turn carries, centrally thereof, a motor meter 12. The means herein-after described for maintaining a permanent connection between the cap and nipple

and meter and nipple, while permitting a limited displacement of the cap and meter relative to the nipple, constitutes, with other collateral novel features, the subject-matter of the present invention.

An annular sleeve 13 is concentrically positioned relative to the nipple 10 and is characterized by an exteriorly reduced lower portion 14 which is exteriorly threaded and screws into the top of the nipple. This sleeve, with its associated parts, is an important feature of the invention for the reason that by its employment the invention may be applied readily to the ordinary plain radiator nipple without necessitating any modification in the construction of the latter. While the particular nipple here illustrated is of the more common interiorly threaded type it will be appreciated that the sleeve 13 may be modified without difficulty to cooperate with nipples of the less common exteriorly threaded type.

The sleeve 13 is provided near its top with two oppositely disposed co-axial pins 15 which project radially from the periphery of the sleeve a short distance. When the sleeve 13 is permanently assembled with the nipple 10 it is desirable, for a reason hereinafter apparent, that the pins 15 project horizontally from the sleeve at a substantial angle to the transverse axis of the automobile. In order to accomplish this in all assemblies and yet have the sleeve screwed into the nipple as far as it will go, it is found advisable to employ, between the rim of the nipple and the shoulder 16 of the sleeve formed by the reduction of the lower threaded portion, one or more slightly compressible resilient washers 17. If the sleeve screws tight with the pins 15 straight across or nearly so it is obviously a simple matter to re-position the pins by adding or removing a washer.

The previously mentioned cap 11 is open on its under side, and is adapted to telescope snugly down over the upper portion of the sleeve 13 when two oppositely disposed short vertical slots or grooves 18 in the cap below the arms 19 thereof are aligned vertically with the projecting pins 15 on the sleeve, as shown in Fig. 1. These slots terminate upwardly in a horizontally disposed annular bayonet groove 20 which is formed in the interior periphery of the cap adjacent the top thereof and serves as

a movable guide channel in which the stationary pins 15 ride when the cap, after being lowered into its fully closed position, is turned to position the arms 19 straight across the radiator and parallel to the transverse axis of the automobile. Just as the cap, in being lowered, reaches its fully closed position, the top of the sleeve, which is provided with an inwardly turned flange 21 for a purpose hereinafter referred to, contacts with a sealing gasket which may be in the form of a slightly compressible resilient pad 22 carried by the cap 11 against the under side of the closed top thereof. By applying a downward pressure to the cap after this contact has occurred the pad will yield sufficiently to permit the bayonet groove 20 to align horizontally with the pins 15, whereupon the cap may be turned under frictional resistance to a position with its arms 19 properly disposed. It will be appreciated from this construction that, due to the gripping frictional action of the pad 22 on the sleeve 13, accidental movement of the cap under the continued vibration and jars of the automobile incident to travel is effectively prevented.

In order to prevent the removal of the sleeve 13 from the nipple 10 after the former has once been properly positioned as described, on the latter, two vertical holes 23 are provided in the sleeve 13 on opposite sides thereof, preferably piercing also the pins 15. These holes extend downwardly from the top of the sleeve to a point just short of the bottom thereof, and, commencing from the sleeve shoulder 16, are exposed and extend downwardly to their extremities as semi-cylindrical grooves formed in the sides of the threaded reduced portion 14 of the sleeve. Pins 24 are inserted in these holes from above and remain with their lower ends flush with the sleeve shoulder 16 while the sleeve is being screwed to its proper position on the nipple. When this position of the sleeve has been attained the pins 24 are driven downwardly into the semi-cylindrical grooves in the sides of the reduced portion 14. As no complementary grooves are present in the nipple to form the other halves of the holes for the pins, the pins cut such vertical grooves in the threads of the nipple as they are forced into their lowest positions. If any portions of the pins 24 still project from the top of the sleeve these are cut off flush with the top, whereby any possibility of removing the pins is eliminated. It will be appreciated that, through this interlocking arrangement of the sleeve with the nipple by the employment of the pins 24, the sleeve, while extremely easy to attach, is permanently fastened to the nipple and cannot be removed.

The motor meter 12 is provided with a circularly flanged pedestal 25 which seats in

a relieved central portion of the top of the cap 11 upon one or more resilient washers 26. The threaded stem 27 of the meter extends downwardly from the pedestal 25 through an aperture 28 in the top of the cap. This aperture is usually larger than required for the meter stem of ordinary size, in order to accommodate meters having oversize stems. The pedestal 25, however, is seated in the relieved portion of the top of the cap, and is accordingly centered relative to the same. About the sides of the aperture 28 the top of the cap is flanged downwardly into a depending band 29.

A conical nut 30 engages the lower portion of the stem 27 below the band 29, and, when turned into its highest position on the stem, bears tightly against the bottom of said band. In order that the stem of the meter 12, like the pedestal thereof, will be centered relative to the cap, the top face of the nut 30 is annularly recessed about its bore to receive the bottom portion of the band 29.

A set screw 31 is passed through the nut 30 into the threaded bore thereof to engage against the stem of the meter and prevent removal therefrom of the nut. While the nut is being tightened against the band 29 on the stem 28, the screw 31 projects from the nut and provides means for turning the latter. After the nut is properly positioned the screw is turned in as far as possible and the head and exposed portion of the shank thereof broken off flush with the surface of the nut. In order to permit this readily, the shank of the screw intermediate its end is preferably weakened by grooving, as shown in Fig. 7. Because of the conical surface of the nut 30, a secure grip cannot be had thereon by a wrench or other tool for the purpose of removing the nut from the stem of the meter.

The previously mentioned resilient pad 22 disposed between the top of the sleeve 13 and the under side of the top of the cap 11 is centrally apertured and fits around the band 29 of the cap. Below the pad 22, and filling the remaining space lengthwise of the band 29 between the pad and top surface of the nut 30 projecting radially of the band, is interposed the circular medial connecting portion 32 of a depending yoke 33, which, like the pad 22, is centrally apertured to fit around the band 29 of the cap. Because of the fact that the nut 30 seats tightly against the bottom of the band 29 of the cap before frictionally engaging to any great extent the portion 32 of the yoke, the yoke may be turned relative to the cap after the motor meter has been rigidly positioned on the cap by the nut. This turning of the yoke is further provided for by the fact that the pad 22 on the upper side thereof will yield sufficiently to permit a turning of the yoke

without an otherwise necessary small amount of play of the latter on the band of the cap.

The yoke 33 is provided on opposite sides 5 of its central apertured portion 32 with depending integral arms 34 which extend downwardly through the sleeve 13 and parallel to the stem of the meter to a point which is below the sleeve when the cap is in 10 its seated position on the nipple. These yoke arms at their lowest extremities are pivotally connected by heavy rivets 35, or other suitable means, to upwardly projecting ears 36 carried on the upper end of an annular anchor or retaining ring 37 at opposite sides thereof. This anchor has an outside diameter which is slightly less than the inside diameter of the sleeve 13 below the flange 21 at the top thereof, and is reduced 15 in diameter at its top and accordingly across its ears 36 to permit the passage of the ears upwardly past the flange 21 when it is desired to raise and turn back the cap from the nozzle for the purpose of filling the radiator. Because of the flange 21 on the sleeve, however, the anchor proper cannot be drawn upwardly past that point.

From the foregoing description it will be appreciated that a cap construction is here 20 presented which permits the raising and lateral displacement, without detachment and removal, of the cap and appliance carried thereby for the purpose of giving unobstructed access to the radiator nipple.

35 I claim:

1. Closure fastening means comprising, in combination with a nipple, a sleeve in permanent engagement with the nipple, a cap adapted to close the passage through the 40 sleeve, means associated with the cap and sleeve for effecting a detachable engagement of the former to the latter, a member interposed between the cap and sleeve to frictionally resist turning movement of the former 45 relative to the latter, and an anchor of greater size than the passage through the sleeve coupled permanently with the cap and positioned in the nipple below the top of the sleeve.

50 2. Closure fastening means comprising, in combination with a nipple, a sleeve in permanent engagement with the nipple, a plurality of lugs projecting from the periphery of the sleeve, a cap adapted to seat over the 55 sleeve and grooved to cooperate with the lugs in a bayonet joint, and an anchor of greater size than the passage through the sleeve coupled permanently with the cap and positioned in the nipple below the top of the sleeve.

60 3. Closure fastening means comprising, in combination with a nipple, a sleeve in permanent engagement with the nipple, a plurality of lugs projecting from the periphery 65 of the sleeve, a cap adapted to seat over the

sleeve and grooved to cooperate with the lugs in a bayonet joint, a member interposed between the cap and sleeve to frictionally resist turning movement of the former relative to the latter, and an anchor of greater 70 size than the passage through the sleeve coupled permanently with the cap and positioned in the nipple below the top of the sleeve.

4. Closure fastening means comprising, in 75 combination with a nipple, a sleeve in permanent engagement with the nipple, a plurality of lugs projecting from the periphery of the sleeve, a cap adapted to seat over the sleeve and grooved to cooperate with the lugs in a bayonet joint, a yielding packing member interposed between the cap and sleeve to frictionally resist turning movement of the former relative to the latter and present a fluid-tight joint therebetween, and 80 an anchor of greater size than the passage through the sleeve coupled permanently with the cap and positioned in the nipple below the top of the sleeve.

5. Closure fastening means comprising in 85 combination with a screw-threaded nipple, a sleeve associated with the nipple in screw-threaded and subsequently keyed engagement therewith, a plurality of lugs projecting from the periphery of the sleeve, 90 a cap adapted to seat over the sleeve and grooved to cooperate with the lugs in a bayonet joint, and an anchor of greater size than the passage in the sleeve coupled permanently with the cap and positioned in the 95 nipple below the top of the sleeve.

6. Closure fastening means comprising in 100 combination with an interiorly screw-threaded nipple, a sleeve associated with the nipple in screw-threaded and subsequently keyed engagement therewith, a plurality of lugs projecting from the periphery of the sleeve, a cap adapted to seat over the sleeve and grooved to cooperate with the lugs in a 105 bayonet joint, and an anchor of greater size than the passage in the sleeve coupled permanently with the cap and positioned in the 110 nipple below the top of the sleeve.

7. Closure fastening means comprising, in 115 combination with a screw-threaded nipple, a sleeve associated with the nipple and provided with a screw-threaded lower portion for engagement with the same, a key disposed in a key-way formed in the cooperating threaded portions of the sleeve and nipple, a cap adapted to close the passage through the sleeve, means associated with the cap and sleeve for effecting a detachable engagement of the former to the latter, and an anchor of greater size than the passage in 120 the sleeve coupled permanently with the cap and positioned in the nipple below the top of the sleeve.

8. Closure fastening means comprising, in 125 combination with an interiorly screw-

threaded nipple, a sleeve associated with the nipple and provided with a reduced exteriorly screw-threaded lower portion for engagement with the same, a key disposed in a key-way formed in the cooperating threaded portions of the sleeve and nipple, a cap adapted to close the passage through the sleeve, means associated with the cap and sleeve for effecting a bayonet joint engagement of the former to the latter, a member

interposed between the cap and sleeve to frictionally resist turning movement of the former relative to the latter, and an anchor of greater size than the passage through the sleeve coupled permanently with the cap, and positioned in the nipple below the top of the sleeve. ¹⁵

In witness whereof I have hereunto subscribed my name.

JOHN F. WHITE.
